UNITED STATES PATENT OFFICE.

RENE BRUNET, OF NEW YORK, N. Y.

SUBMARINE.

1,168,707.

Specification of Letters Patent.

Patented Jan. 18, 1916.

Application filed July 31, 1915. Serial No. 42,979.

To all whom it may concern:

Be it known that I, RENE BRUNET, a citizen of Canada, residing at New York, in the county of New York and State of New York, have invented new and useful Improvements in Submarines of which the following is a specification.

The present invention relates to submarines, and, more particularly, to safety device for same, in the form of compartments in which the crew may take refuge, in the event of accident to the craft. The safety compartments are all provided with means of communication with the interior of the submarine and also with the outside by means of suitably operated doors as herein-after described.

The object of the present invention is to provide a simple yet efficient means whereby the crew may make their exit from the craft in case of emergency, a further object is to so construct the device so that its operation will be positive, and also comparatively inexpensive to manufacture, another object is to provide means for preventing the water pressure from forcing the crew against the walls of the safety compartments, other objects will be obvious from the following description and the subjoined claims.

Referring to the accompanying drawings, in which similar reference characters refer to similar parts in the several figures:—Figure 1 is a plan view of a submarine showing my invention. Fig. 2 is a sectional view on the line 2—2 of Fig. 1. Fig. 3 is an enlarged horizontal section of a portion of the submarine. Fig. 4 is a diagrammatic view showing the mechanism and circuits for operating the safety doors.

Referring to Fig. 1 I have shown two compartments 10 and 11 communicating with the interior of the submarine by doors 12. These doors may be held securely closed by suitable latches 13. On the outer wall of the submarine there are doors 14 which are normally held in closed position by a suitable latch 15. At the rear end of each door is secured a rack 16. Pinions 17 are secured to the armature shafts of the motors 18. The circuits of the motors 18 are controlled by a pole-changing switch 19, by means of which the current from the storage battery 20 may be caused to flow in opposite direc-

tions thereby reversing the motors 18 when so desired.

In the walls of the compartments 10 and 11 I provide vent passages 21. Levers 22 pivoted at 23 are provided with plugs 24 adapted to close the vent passages 21. The levers 22 are provided with toes 25 adapted to coact with the lugs 26 integral with racks 16.

The interior of the walls of the chambers 10 and 11 is provided with a plurality of bars 27 spaced away a short distance from the inner walls of said chambers similarly. The doors 12 are also provided with a plurality of bars 27.

From the foregoing it will be obvious that if this submarine becomes disabled while submerged, the crew will be able to escape as will presently be described. The door 12 may be opened and the crew may enter either one of the compartments 10 or 11, the latch 13 on the door 12 may be so constructed that when the door is closed it will automatically lock. The occupants of the safety compartment may then un-lock the sea-doors 14 and operate the switch 19 so as to put the motors 18 in circuit with storage batteries 20. This will cause the pinions 17 to rotate in the directions of the arrows shown in Fig. 4. These pinions in turn will draw back the racks 16 and the doors 14 attached thereto. As the doors 14 gradually open, the water will gradually flow into the compartments 10 and 11 and fill the same. It will be obvious that if some safety means were not provided the great water pressure thus obtained would cause the occupants in the safety compartments to be forced against the walls of the compartment, but by providing the bars 27 it will be readily seen that the crew will be forced against these bars which being spaced away from the walls will permit the water to flow all around said bars and therefore equalize the pressure on the said occupants of the compartments, hence they would be able by their own physical efforts to free themselves from the compartments. It being understood that the occupants before entering the compartments may have been equipped with divers or other suitable devices for under water travel.

The operation of the air vents will now be

described: As the doors 14 move back, the lugs 26 will engage the toes 25 of the levers 22 and cause the air vents 21 to close and thereby prevent the entrance of water into the submarine proper. Spring latches 28 will securely hold the levers 22 in their closed positions until manually released.

Having thus described my invention what I claim is:—

- 10 1. In a submarine a plurality of safety compartments provided with a plurality of bars spaced a short distance away from said walls, means for communicating with the interior of the submarine and said safety compartments, sliding doors for said safety

compartments communicating with the outside, means for operating said latter doors, means for controlling the operating means of said doors.

2. In a submarine a plurality of safety compartments, the inner walls of which are provided with a plurality of bars spaced away a short distance from the walls.

Signed at New York in the county of New York and State of New York, this 29th day of July A. D. 1915.

RENE BRUNET.
